UNITED STATES PATENT OFFICE

163,673

DRINKING TUMBLER

Charles O. Bliss, Los Angeles, Calif.

Application February 20, 1950, Serial No. 8,024

Term of patent 14 years

(Cl. D36—8)

To all whom it may concern:

Be it known that I, Charles O. Bliss, a citizen of the United States, residing at 6674 Santa Monica Boulevard, Los Angeles, in the county of Los Angeles and State of California, have invented a new, original, and ornamental Design for a Drinking Tumbler, of which the following is a specification, reference being had to the accompanying drawings, forming part thereof.

Fig. 1 is a perspective view of a drinking tumbler embodying my new design;

Fig. 2 is a top plan view thereof; and

Fig. 3 is an axial sectional view of one side thereof.

I claim:

The ornamental design for a drinking tumbler, as shown.

CHARLES O. BLISS.
